Primary Examiner—Pamela J. Burgess**Attorney, Agent, or Firm—Pearne, Gordon, McCoy & Granger LLP****[57] CLAIM**

The ornamental design for a plate rack, as shown and described.

DESCRIPTION

FIG. 1 is a front, top and side perspective view of a first embodiment of a plate rack, showing my new design;

FIG. 2 is a front elevational view thereof;

FIG. 3 is a top plan view thereof;

FIG. 4 is a right side elevational view thereof, the left side elevational view being a mirror image;

FIG. 5 is a rear elevational view thereof;

FIG. 6 is a bottom plan view thereof;

FIG. 7 is a front, top and side perspective view of a second embodiment of FIG. 1, the only difference from the first embodiment is the number of plate mountings; and,

FIG. 8 is a front, top and side perspective view of a third embodiment of FIG. 1, the only difference from the first embodiment is the number of plate mountings and bracket supports.
